(57) **CLAIM**

The ornamental design for a ground fault circuit interrupter, as shown and described.

DESCRIPTION

FIG. 1 is a bottom perspective view of a ground fault circuit interrupter showing our new design;

FIG. 2 is a top perspective view thereof;

FIG. 3 is a bottom plan view thereof;

FIG. 4 is a front elevation view thereof;

FIG. 5 is a top plan view thereof;

FIG. 6 is a left side elevation view thereof; and,

FIG. 7 is a right side elevation view thereof.

The broken line portion of the figure drawings is included to show unclaimed detail within the six screw holes of FIG. 3, and within the center of the power cord in FIG. 7 only, and forms no part of the claimed design.
